UNITED STATES PATENT OFFICE.

MARK LANE FRANKLIN, OF OWEN SOUND, ONTARIO, CANADA.

SAFETY DEVICE FOR IRONS.

Application filed September 8, 1923. Serial No. 661,667.

To all whom it may concern:

Be it known that I, MARK L. FRANKLIN, a citizen of Dominion of Canada, residing at Owen Sound, in the Province of Ontario and Dominion of Canada, have invented new and useful Improvements in Safety Devices for Irons, of which the following is a specification.

This invention relates to attachments for electric irons and has for its object the provision of an automatic thermostatic control switch or circuit breaker designed for association with any already existing iron and acting automatically to break the circuit and cut off the current supply to the iron in case the temperature thereof reaches an excessive point which might result in scorching the clothes being pressed or ironed, the device automatically reclosing the circuit when the temperature is reduced by cooling.

An important and more specific object is the provision of a device of this character which may be adjusted so as to regulate the temperature.

An additional object is the provision of a thermostatic attachment which will be simple and inexpensive in manufacture, easy to install, positive in action, efficient and durable in service and a general improvement in the art.

With the above and other objects and advantages in view the invention consists in the details of construction to be hereinafter more fully described and claimed and illustrated in the accompanying drawings, in which:

Figure 1 is a side elevation of an iron equipped with the device,

Figure 2 is a plan view of the device with the cover thereof removed,

Figure 3 is a longitudinal section,

Figure 4 is a diagram of the electric circuit and

Figure 5 is a detail elevation of the movable contact.

Referring more particularly to the drawings the letter A designates an electric iron of any ordinary or preferred type equipped with the usual handle B and provided internally with a resistance or heating coil C. Ordinarily the terminals of this coil are brought out to posts D and E forming part of the socket structure F into which is inserted the plug G connected with the current feed wires H and I. All the above described parts are old and well known.

In carrying out my invention I provide a

thermostatic device which comprises a casing 10 adapted to be secured upon the iron A by suitable screws 11. This casing has a removable cover 12 held in place by screws 13 which may be removed when access is required to the interior for making repairs or adjustments. The casing is provided with a lining 14 of suitable insulating material so as to avoid any possible short circuits, and secured upon one end thereof is a shell 15 containing a block 16 of insulating material from which project terminal posts 17 and 18. This shell is adapted to receive a terminal plug 19 containing contacts adapted to engage the posts 17 and 18. The feed wire H of the current supply line is brought into the plug G in the usual manner, while the wire I is brought down and connected with the contact which engages the post 17, the contact engaging the post 18 having connected therewith a wire 20 which is brought into the plug G and connected with one of the contacts therein. In this way it will be seen that the contacts in the plug 19 are interposed in series with one of the feed wires, so that the thermostatic control device is in series with the heating coil C as indicated in the diagram shown in Figure 4.

Within the casing 10 is a base 21 of insulating material held in place by screws 22 or the like, and secured upon this base is a bowed metallic strip 23 having its ends anchored as shown at 24 and 25. Connected with the binding screw 25 is a strip or wire 26 which lies against the lining of the adjacent end wall and which is connected with the post 18. Rising from the base or block 21 is a threaded post 29 formed with an enlargement 30 which is embedded in the base, and connected with this enlargement is a strip 28 leading to and secured to the post 17. Threadedly and adjustably engaged upon the upper end of the post 29 is a socket member 27 which constitutes a contact normally engaging the underside of the bowed strip 23. This socket member is split as shown in Figure 5 whereby it will frictionally grip the post and not be accidentally jarred so as to turn when such is not desired. By adjusting this socket member 27 it is obvious that the sensitiveness of the thermostat may be regulated. It is of course apparent that when the contact 27 engages the bowed leaf or strip the support is closed through the heating coil C of the iron.

In the operation it will be apparent that

in case the iron becomes overheated at any time, the expansion of the strip 23 will cause it to bow more acutely or abruptly than is indicated in Figure 3, whereupon it 5 will move upwardly out of engagement with the contact 27, thus breaking the circuit so that no more current will pass to the iron until the latter has cooled off to a certain extent, at which time the strip 10 23 will contact and be bowed less abruptly so that it will again engage the contact 27.

While I have shown and described the preferred embodiment of my invention it is of course to be understood that I reserve the 15 right to make such changes in the form, construction and arrangement of parts as will not depart from the spirit of the invention or the scope of the subjoined claims.

Having thus described my invention I 20 claim:

1. In an electric iron, a thermostatic control device comprising a metallic casing adapted to be mounted upon the iron, a block of insulating material within the casing, a bowed metallic strip anchored at its 25 ends upon said block, an attaching shell at one end of the casing, a plug therein, a pair of terminal posts extending through said plug, one post being connected with one 30 end of said strip, a contact connected with the other post and extending within the

bottom portion of the block, and a contact normally engaged by the strip and connected with said first named contact.

2. A device of the character described 35 comprising a metallic casing provided with means for attachment upon an electric iron, a base of insulating material within the casing, a bowed strip having its ends anchored upon the base, terminal posts, a conducting strip connected with one post and one end of said strip, a contact located within a recess in the base and connected with the other post an upstanding threaded post connected with said contact, and a threaded 40 socketed contact on said post normally engaged by said bowed strip.

3. A device of the character described 45 comprising a metallic casing provided with means for attachment upon an electric iron, a base of insulating material within the casing, a bowed strip having its ends anchored upon the base, terminal posts, a conducting strip connected with one post and one end of said strip, a contact located 50 within a recess in the base and connected with the other post an upstanding threaded post connected with said contact, a threaded socketed contact on said post normally engaged by said bowed strip, the socketed contact being adjustable upon the post. 55

MARK LANE FRANKLIN. 60
